UNITED STATES PATENT OFFICE.

EMILE PAUL DUMANOIS, OF PARIS, FRANCE.

INTERNAL-COMBUSTION ENGINE.

1,273,834.

Specification of Letters Patent. Patented July 30, 1918.

Application filed March 18, 1914. Serial No. 825,656.

To all whom it may concern:

Be it known that I, EMILE PAUL DUMANOIS, citizen of the French Republic, residing at Paris, Department of the Seine, in France, 5 have invented certain new and useful Improvements in or Relating to Internal-Combustion Engines; and I do hereby declare the following to be a full, clear, and exact description of the invention, such as will 10 enable others skilled in the art to which it appertains to make and use the same.

The present invention relates to internal combustion engines and more particularly to those in which air is compressed to a high 15 pressure before the injection of the fuel so as to obtain the temperature requisite for the ignition. In engines of this kind the constructional difficulties are considerable when the bore of the cylinder exceeds certain 20 limits. The present invention has for its object a device for conjugating two cylinders of different dimensions; the combustion is effected in the smaller cylinder either by self-ignition under a sufficient 25 pressure or through the medium of a spark plug or any other suitable means. As regards the large cylinder it operates either only as an expansion cylinder, with the exhaust gases of the smaller cylinder or as a 30 combustion and expansion cylinder by the ignition, with the aid of the gases of the small cylinder, of an explosive mixture the pressure of which cannot exceed a predetermined limit. Such groups or pairs of 35 cylinders may be connected in any number so as to obtain a predetermined total power.

In the accompanying drawing:

Figure 1 shows by way of example, in 40 vertical section a construction of the engine according to the invention and operating with self-ignition under pressure;

Fig. 2 is a plan of the device shown in Fig. 1;

Fig. 3 is a vertical section of a modified 45 form of piston in which a valve is employed in the piston for controlling communication between the main cylinder and the auxiliary cylinder;

Fig. 4 is a vertical section of an engine 50 similar to that shown in Fig. 1, but operating upon the two-cycle principle;

Fig. 5 is a vertical section of a modified 55 form of engine;

Fig. 6 is a plan view of the engine shown in Fig. 5;

Fig. 7 is a vertical section of an engine similar to that shown in Fig. 5, but operating on the two-cycle principle;

Fig. 8 is a vertical section of a modified 60 form of the engine shown in Fig. 5;

Fig. 9 is a plan view of the engine shown in Fig. 8;

Fig. 10 is a vertical section of a modified 65 form of the engine shown in Fig. 8; and

Fig. 11 is a plan view of the engine shown in Fig. 10.

Referring to the drawings, a large piston 1 (Fig. 1) moves in a cylinder 2 and is provided, at its upper part, with a small piston 3. After a certain period of the compression stroke, the piston 3 engages in the cylinder 4 which is provided above the cylinder 2 thus imprisoning a certain quantity of air which is already compressed and heated. The clearance of the cylinder 2 is such, that at the end of the compression, the pressure obtained is not sufficient to effect the self-ignition; the clearance of the cylinder 4 is such that the pressure at the end of the compression and therefore the temperature can produce self-ignition of the fuel atomized when the injector valve 5 of the injector 5' is opened, with a certain amount of lead or advance. The whole or a portion of the fuel is introduced by injection during the compression stroke, the injection continuing after the upper dead center is reached. The combustion begins in the cylinder 4 and is completed in the cylinder 2 only at the moment the piston 3 leaves the chamber 4 in the case of the construction shown in Fig. 1. If desired, a passage 6 may be provided, which serves to conduct a portion of the injected fuel and ignited gases to the cylinder 2, so as to permit of the creation of predetermined pressures in 4 and in the large cylinder. These openings may be provided with valves, as shown in Fig. 3. In this figure, a sleeve 1' is inserted in the body of the piston to receive a differential piston 1''. This differential piston is mounted to slide in the sleeve 1' and is provided with a portion s' which normally bears against the valve seat s'' formed on the sleeve 1', as clearly shown in the drawing. The valve is normally held closed by a spring R interposed between the lower part of the valve and a plug B screwed into the lower extremity of the sleeve 1'. When the pressure 105 in the auxiliary cylinder exceeds that in the main cylinder, by a predetermined amount,

95

105

110

the valve is opened to establish communication between the two cylinders by means of the passages 6. The combustion therefore begins in the latter at the same time and is completed as above described. The duration of the lifting of the injector valve 5 may be prolonged beyond the moment when the piston 3 leaves the cylinder 4; even when not injecting fuel, the supplied additional air 10 assists the mixing of the gases. The fluid-tightness of pistons 1 and 3 may be obtained by means of the usual piston rings. 7 and 8 are suction valves adapted to be controlled simultaneously; 9 and 10 are exhaust valves 15 controlled in a similar manner; 11 is the valve serving for the starting the engine by means of compressed air. The device is also applicable to two-cycle cylinders; as shown in Fig. 4. In this case, the exhaust valves 9 and 10 are replaced by an exhaust port 9', so located in the cylinder wall as to be opened by the piston near the end of its down stroke. This port discharges into an exhaust conduit 10'.
 Figs. 5 and 6 show a modification in which the small piston is independent of the large one, in the case of four-cycle engines. The pistons 12 and 13 are connected to cranks mounted at the same or approximately the same angle; they operate in the cylinders 14 and 15 respectively, the clearances of which are such that at the end of the travel or stroke in 14 the pressure requisite for self-ignition is obtained while in 15 a pressure is obtained which is below a predetermined limit. The piston 12 may be operated from the driving shaft like the cylinder 13 by a connecting rod and crank or by any other means.
 The operation is as follows:
 At the end of the common compression stroke, the operation of the injector valve 16 of the cylinder 14 or any other suitable device, effects the injection of fuel with a certain advance determining ignition in the cylinder 14. The whole or a portion of the fuel may be introduced by injection during the compression stroke, the injection continuing after the upper dead center is reached. The valve 17 or an equivalent device, is controlled in such a manner as to open with a suitable delay, into cylinder 14 and through the passage 18, communicates the combustion to the cylinder 15. 17 and 18 may be replaced, if desired, by one or more openings which may or may not be provided with valves. In the interior of the cylinder 15 either the whole of the fuel or only a portion thereof has been atomized 20 through 19 during the compression stroke, the injection being adapted to continue after the dead-point is reached and may be of a continuous nature or not. If desired, 19 may be dispensed with, and the whole fuel

may be injected through the injector 16', the gases penetrating under the valve 17 and the passage 18 into the cylinder 15 where the combustion is completed. The cylinder 15 is provided with an exhaust valve 20 and a suction valve 21 and the cylinder 14 is 60 provided with an exhaust valve 22, the suction taking place through a special valve (not shown) or through the passage 18 and the valve 17. Moreover, if necessary, the valve 22 may be also dispensed with, the 70 valve 17 being then controlled in such a manner as to insure the communication between 14 and 15 during the starting of the engine by means of compressed air admitted through 23 and 24 and also during the 80 whole cycle with the exception of the entire compression stroke or a portion thereof.

Fig. 7 shows an engine similar to that shown in Fig. 5, but operating on the two-cycle principle. In this modification, the 85 exhaust valve 20 is replaced by a port 20' located in the cylinder wall to discharge the exhaust gases into the exhaust conduit 15'. Likewise, the smaller cylinder 14 is provided with a corresponding port discharging into an exhaust conduit 14'.
 In Figs. 8 to 11, modifications have been shown in which it has been proposed to avoid the high pressure requisite for the self-ignition. The fuel is atomized in the 95 small cylinder during the compression stroke and its ignition is produced at the end of the stroke with a suitable advance, by means of an electric spark plug or any other device usually employed in conjunction with internal combustion engines. The valve between the two cylinders may be eliminated, the two cylinders being thus in constant communication through a passage connecting the two combustion chambers; in this case, the piston of the small cylinder may be dispensed with, and the latter may be suitably formed.

In Figs. 8 and 9, the piston 1 moves in the cylinder 2 which is in constant communication with the small cylinder 25 through the conduit 26. 7 and 8 are suction and exhaust valves of the cylinder 2, 27 is the valve for supplying compressed air, and 5 is the injector valve or any other suitable device for spraying fuel into the cylinder 2; 9 is the exhaust valve of the small cylinder, 28 its fuel atomizing apparatus and 29 the sparking plug.

The operation is as follows in the case of 120 a four-cycle engine:

During the expansion stroke the gases of 25 expand in 2 through the channel 26; during the exhaust stroke, 9 and 8 are open, during the suction stroke, 7 is open; during the compression stroke, a portion of the air contained in 2 flows through 25, 28 being open at the same time; at the end of the

compression stroke ignition is produced in 25 by 29 and the ignited gases produce conflagration in the cylinder 2 in which the whole or a portion of the fuel may have been introduced through 5 during the compression stroke, the injection continuing, if necessary, after the dead-point is reached.

The valve 9 may be open during the beginning of the period of compression so as to insure a scavenging of 3 through the medium of 26. Moreover, if necessary, 9 may be dispensed with by giving the conduit 26 a suitable section. The device is also applicable to two-cycle engines, the valve 6 being replaced by suitably disposed ports or any other device.

Figs. 10 and 11 show a modification in which the small cylinder is placed above the large one in the case of four-cycle engines. The large piston 30 which moves in the cylinder 31, communicates with the small cylinder 32 through one or more orifices 33, 34 is the fuel injector valve or other suitable device; 35 and 36 are the suction and exhaust valves of 31; 37 is the spark plug or an equivalent device; 38 is the exhaust valve of 32; 39 is the valve for supplying compressed air.

The operation is as follows:

During the compression stroke, the whole of the fuel or a portion thereof, is introduced through 34; at the end of this stroke the ignition takes place through 37 with a suitable advance and the ignited gases propagate the conflagration to 38.

The operation during the expansion, exhaust and suction strokes, is the same as in the device which forms the object of Figs. 1 and 2. 38 may be dispensed with, if desired, under the same conditions.

The operation is similar with two-cycle cylinders, 36 being replaced by any other suitable device.

I claim:

1. In an internal combustion engine, the combination with the working cylinder and its piston, of an auxiliary chamber, an atomizer for beginning the injection of at least a part of the fuel in the auxiliary chamber during the compression period and continuing such injection after the piston reaches the end of its upward stroke, a passage placing the auxiliary chamber in communication with the working cylinder, and a valve positioned in said passage, and operable to open said passage when a predetermined pressure is reached in the auxiliary chamber.

2. In an internal combustion engine, the combination with a working cylinder and its piston, of an auxiliary chamber, an extension on the piston operable in the chamber, an atomizer for injecting fuel into said chamber during the compression period and continuing such injection after the piston reaches the end of its upward stroke, the clearance between the piston and working cylinder being such that the fuel is not compressed sufficiently to cause self ignition, and the clearance between the extension and the auxiliary chamber being such that the fuel is compressed sufficiently to cause self ignition, and means for placing the auxiliary chamber in communication with the working cylinder.

In testimony whereof I affix my signature, 75
in presence of two witnesses.

EMILE PAUL DUMANOIS.
